SECTIONAL HEADER FOR AUTO RADIATORS

Michael J. Tomel, Richmond Hill, N. Y.

Application December 12, 1947, Serial No. 791,237

1 Claim. (Cl. 257—125)

1

The present invention relates to an improved header for automobile radiators, and the principal object of the invention is to provide a header which is such in construction that it permits access to be had to tubes in the core assembly for cleaning purposes.

It is a matter of common knowledge that there are at least three well-known and generally accepted methods of cleaning automobile radiators. For example, there is the so-called reverse flush procedure utilizing water under pressure, but it has been my experience that this is a "hit or miss" method and is not usually successful. Secondly, there is the generally described "boiling out" method which, in my judgment, is superior to the reverse flush procedure, but here again, it has been my experience that the stated second method is not as efficient as is generally claimed by radiator repairmen. The best-known method is that wherein the accumulations in the core tubes are rammed or pushed out by "roding" same. It is the consensus of opinion that the latter method is best suited for ordinary purposes but requires considerable laborious effort and time and necessitates the workman melting the top tank or header from the core tubes and subsequently, replacing same. There is another objection and that is the roding method makes it necessary to take the radiator off of the car and the expense attached to a complete successful job is often considerable.

The purpose of the present invention is to so construct the header that the cover or top section is removable, whereupon it exposes the upper open ends of the tubes and permits same to be plunged out with the usual rod means.

In carrying out the invention, I provide a sectional header, the lower section constituting a base and being of receptacle form and rigidly secured to the upper open ends of the tubes and the cover section being latched or otherwise connected to the first section and the two sections being properly joined together for fluid-tight action.

Other objects and advantages will become more readily apparent from the following description and the accompanying illustrative drawings.

In the drawings:

Figure 1 is a perspective view of a sectional header, constructed in accordance with the principles of the present invention.

Figure 2 is a rear elevational view of same.

Figure 3 is an end view observing Figure 2 from either end.

Figure 4 is a horizontal section on the plane of

the line 4—4 of Figure 2, looking in the direction of the arrows.

Figure 5 is a cross-section, on an enlarged scale, on the line 5—5 of Figure 2, looking in the direction of the arrows.

Reference is had first to Figure 5, wherein the core or tube assembly is denoted by the numeral 1, the same being made up of conventional-type vertical tubes 8, open at opposite ends. The improved sectional header is denoted by the numeral 9 and comprises a receptacle-like base section 10, which is secured to the upper ends of the tubes, the latter projecting into the section 10, in the manner shown. The upper edges of the walls of said section 10 are fashioned into an endless V-shaped adapter flange 11. The upper complementary section of the header constitutes a cover and is denoted by the numeral 12, and is a rectangular shell which is open at its bottom. The lower ends of the walls forming said shell are fashioned into beads 13 and the latter are seated removably in the channel provided by said flange 11. In practice, a suitable sealing compound or gasket means is provided (not shown) to insure an effective liquid-tight seal between parts 11 and 13. Also, a neck is provided on the rear side, as at 14, to accommodate the customary circulating hose (not shown). The top of the shell is provided with a filler neck 15 and closing cap 16.

Suitable means is provided for releasably latching the sections 10 and 12 together. I prefer the means shown in the drawings comprising a plate 17 rigidly secured to an end of the base section and provided with a keeper hook 18, to accommodate a link 19 forming a part of a toggle-type latch. The bail portion of the latch is indicated at 20 and the two parts are hingedly connected in the manner shown, and the arms of the bail are hingedly mounted on ears provided on a foundation plate 21, secured to the end of the upper cover section 12. This sort of latching means provides the necessary take-up action and insures proper mating relation of the upper and lower sections 12 and 10 respectively.

I next call attention to the strainer screen 22, which is preferably provided, and is seated on supporting pins, or the like, 23 provided in the base section 10.

It is evident that with the construction shown, the latches may be readily released and the sections 10 and 12 disconnected, the section 12 being bodily removed. Then, the screen 22 is lifted out and access is had to the upper open ends of the core tubes 8. Thus exposed, the tubes may

be readily cleansed and scaled under the aforementioned "roding" method.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention what is claimed as new is:

A sectional header for automobile radiators comprising a receptacle-like base section including a bottom with tube openings for passage of the upper end portions of radiator tubes and including marginal walls, the upper edge portions of said walls being formed with an endless seating and assembling flange, said flange being substantially V-shaped in cross section and providing a seating channel, and a cover section correspond-

ing in shape and proportions to the base section, said cover section having wall portions and said wall portions having edges fashioned into a seating and assembling bead, said bead also being endless and seated in the stated channel, and a horizontally disposable filtering screen, said screen being an independent unit and having a marginal rim, and studs projecting from the walls of the base into the interior of the base and removably seating said screen, the latter being mounted on the studs downwardly of said V-shaped flange.
